UNITED STATES PATENT OFFICE.

HANS KARL SCHRAMM, OF NEW YORK, N. Y.

ENVELOP.

1,307,421.

Specification of Letters Patent. Patented June 24, 1919.

Application filed December 12, 1917. Serial No. 206,823.

To all whom it may concern:

Be it known that I, HANS KARL SCHRAMM, a citizen of the United States, residing at New York, in the county of New York and 5 State of New York, have invented certain new and useful Improvements in Envelops, of which the following is a specification.

My invention relates to new and useful improvements in envelopes, which are folded 10 from a single blank of paper upon the inside of which a letter may be written, then the paper folded and sealed to form an envelop embodying the essentials of durability, inexpensiveness to manufacture and efficiency in practice.

An important object of my invention is to provide a device of the above mentioned character having a window therein, which is arranged to surround the name and address 20 of the addressee, when the blank is folded and sealed to form the envelop; and means whereby the window will be held securely around the name and address of the addressee to retain the contents of the letter 25 intact during transportation of the same, and at the same time the letter may be readily opened by the addressee regardless of the retaining feature.

Other objects and advantages of my invention will be apparent during the following description.

In the accompanying drawings forming a part of the description and wherein like numerals are employed to designate like parts throughout the same,

Figure 1 is a plan view of the inside of the blank before being folded.

Fig. 2 is a plan view of the outside of the device after it has been folded once.

Fig. 3 is a plan view of the outside of the envelop after it has been folded twice.

Fig. 4 is a sectional view taken on the line 4—4 of Fig. 2, and

Fig. 5 is a sectional view taken on the line 45 5—5 of Fig. 3.

In the drawings wherein is shown a preferred embodiment of my invention, the numeral 1, designates a single blank of paper which has the marginal edges of one side 2, 50 and half the top 3, and bottom 4, removed therefrom. Adjacent the top edge 3, upon the inside of the blank 1, I provide a space for the name and address of the addressee which is surrounded by the dotted lines 5.

55 The other half of the blank 1, is then left with the marginal side 6 and one half of the

marginal top edge 7, and bottom edge 8. A line of perforations 9, extends parallel to the margin 7, and is spaced from the marginal edge the same distance as the distance from the edge 3 to the margin 7. This line of perforations extends the entire length of the marginal edge 7. Similar lines of perforations 10 and 11 are provided in the marginal edges 6 and 8 respectively. All the marginal edges 6, 7 and 8 are gummed for a purpose which will presently appear. In this side of the blank adjacent the top margin 7, is an opening or window 12 which is cut from the blank 1, and adapted to surround the dotted area 5 on the opposite side of the blank, when the blank has been folded along its longitudinal axis 13. I provide the perforations 14 to surround the window 12 a small distance from the marginal edges of the window. The portion of the blank included by the marginal edges of the window 12, and the perforations 14, are gummed for a purpose which will presently appear.

80 The name and address of the addressee is adapted to be written on the blank, surrounded by the dotted line 5, and the body of the letter is to be written upon the blank below the window 12, and the dotted lines 5. After 85 the letter has been completed the gummed edge around the window 12 is moistened and the blank is folded along the longitudinal axis 13, so that the gummed marginal edge of the window will stick around the dotted 90 line 5, and the name and address of the addressee. By gumming the marginal edges of the window, the addressee's name and address will always be positioned correctly in the window and the marginal edges of the 95 window will be prevented from overlying the said address. The gummed marginal edges 6 and 8 are then moistened and folded along the perforations 10 and 11, to embrace the edges 2 and 4 respectively to be securely 100 held to the outside of the blank, as more clearly shown in Fig. 2. The blank is then folded along its transverse axis 15 so that the lower part 16, will lie in back of the upper part 17, as more clearly shown in 105 Fig. 3. The gummed marginal edge 7, is then moistened and bent back and pasted to the lower portion 16 along the margin 8. After folding the blank in the manner set forth it will be apparent that the name and 110 address of the addressee will be clearly visible through the window 12.

After the letter reaches its destination, the addressee will take the edges 13 and pull the same from the portion 16 to which it is attached by the gummed edge 7, and detach 5 the portion 17 from the portion 16 by tearing along the perforations 9. Then the edge 3 is grasped and pulled outwardly so as to tear the perforations 10 and 11. At the same 10 time the gummed marginal edge of the window 12 will stick around the dotted line 5 and will be torn from around the window 12 along the perforated portions 14. It will be seen that the letter is now in an open position and the contents thereof may be examined. 15

It is to be understood that the form of my invention herein shown and described is to be taken as a preferred embodiment of the same and that various changes in the shape, 20 size, and arrangement of parts may be resorted to without departing from the spirit of the invention or the scope of the subjoined claims.

Having described my invention I claim:

25 1. An envelop comprising a blank, adapted to be folded first upon itself upon its longitudinal axis then again upon itself upon the transverse axis of the folded blank provided by the longitudinal fold, said blank 30 having one of its entire longitudinal marginal edges and one half of its transverse top and bottom marginal edges cut away parallel to their respective opposite marginal edges, and the remaining longitudinal marginal edge and transverse top and bottom edge being gummed and provided with lines

of perforations extending the entire length of said edges, whereby the gummed longitudinal marginal edge is folded and adhered to the back of its opposite edge, and the 40 transverse bottom gummed edge is folded and adhered to the back of this adjacent edge of the blank when the blank is first folded upon its longitudinal axis, while the transverse top marginal gummed edge is adhered to the front of the opposite portion of the transverse bottom edge after the blank 45 has been folded again upon its transverse axis.

2. A blank adapted to be folded in half 50 upon itself, one half of said blank being provided with an addressee space, the other half of said blank being provided with an opening to surround the addressee space when the envelop is folded, the inside marginal 55 edges of said opening being gummed to adhere to the first mentioned half of the blank and around the said addressee space when the said first mentioned half is folded upon the last mentioned half, to prevent unauthorized opening of the envelop and a line of perforations extending around said opening in spaced relation thereto whereby the halves of the envelop may be separated by severing the gummed edges of the second named half 60 65 therefrom.

In testimony whereof I affix my signature in presence of two witnesses.

HANS KARL SCHRAMM.
